UNITED STATES PATENT OFFICE

FRANK L. WESTERMAN, OF WYOMING, OHIO

BOOKLET

Application filed March 14, 1930. Serial No. 435,975.

This invention relates to memorandum tablets and particularly to a unitary article of manufacture including a pad, a pencil and an information book.

5 The object of this invention is to coordinate said elements into a compact unitary structure which expedites their joint and individual use.

A further object of the invention is to provide a memorandum unit which is adapted to be ornamental, attractive to the eye, suitable for advertising, and which is provided with a pad, a pencil, and an information book coordinated structurally to maintain the 15 ornamental nature of the unit.

Other objects and advantages will be more fully set forth in the description of the accompanying drawings forming a part of this specification, in which:

20 Figure 1 is a front view of the novelty reference pad showing the information book folded up in its position when not in use and also showing the scratch pad and pencil of the novelty.

25 Figure 2 is a face view similar to Figure 1 but showing the information book in use and unfolded from behind the ornamentation at the top of the novelty.

Figure 3 is the side view of Figure 2.

30 Figure 4 is the side view of the top portion of Figure 1 illustrating the information book in folded position.

The memorandum unit comprises a backing 1 preferably of stiff cardboard. To this 35 a paper scratch pad 2 is secured by means of a member 3 engaging over the upper margin of the pad. The scratch pad can therefore be removed when desired. However, any conventional fastening means may be used 40 to mount the pad.

An information book 4 is also secured to the backing by gluing clips or otherwise. This book can contain a calendar, telephone numbers, or other information.

45 This book preferably comprises a single sheet folded upon itself to provide a plurality of equal sized pages collapsible upon one another to occupy a small space, one outer page secured to the backing. The book may 50 be reinforced at the lines of fold by means of

strips of tape 4^a or it may be made of separate pieces for each page secured together by the tape. The other outermost page is secured to a cover 5 which may be dispensed with if the paper of the book is sufficiently heavy. This cover is provided with a tab 6 by which the book is opened.

The book is collapsed or held against the backing by means of a draw string 7 which is attached to the cover or outer page of the book and extends through apertures 8 in each page and downward at the rear of the backing to extend through a small aperture 9 in the backing. Pulling this draw string, therefore, closes the book and the friction of the string with the walls of the aperture 9 in the backing holds the book closed. On the end of the draw string is a handle 10 or an equivalent instrumentality for drawing the draw string. As disclosed, the handle is also a pencil. The friction on the draw string may be increased to the desired extent by threading the draw string through a plurality of apertures in the backing, (not shown) or by any other friction means. In this way the ease with which the book can be opened or closed is determined. An aperture is provided at the top of the backing, as at 11, and serves as a means for hanging the memorandum unit on a nail or hook.

As disclosed, the backing is outlined to represent a human figure. The scratch pad is positioned to coincide with the apron and the book is positioned to coincide with an article, such as a basket carried on the head of the figure.

Many ornamental designs can therefore be predicated upon this structure.

Having described my invention, I wish to be limited only by the ensuing claims.

I claim:

1. A memorandum unit, comprising, a backing, a sheet folded upon itself into a plurality of pages attached to said backing by an outer page, a draw string attached to the other outer page, said draw string extending through said pages and the backing, and means providing frictional contact between said draw string and backing to retain the pages in compact relationship.

2. A new article of manufacture, comprising, a backing, a fan folded booklet attached to said backing, a draw string passing through the pages of said fan folded booklet the drawing of which is adapted to close said booklet, said draw string having a drawing instrumentality attached to the end thereof.

5 In witness whereof, I hereunto subscribe my name.

10
